C. DE ROCHEFORT-LUCAY,
ALARM FOR MOTION PICTURE FILM REELS,
FILED DEC. 16, 1920.

2 SHEETS—SHEET 2.

UNITED STATES PATENT OFFICE.

CLAUDE DE ROCHEFORT-LUCAY, OF NEW YORK, N. Y.

ALARM FOR MOTION-PICTURE-FILM REELS.

Application filed December 16, 1920. Serial No. 431,253.

To all whom it may concern:

Be it known that I, CLAUDE DE ROCHEFORT-LUCAY, a citizen of France, residing at New York, in the county of New York and State 5 of New York, have invented certain new and useful Improvements in Alarms for Motion-Picture-Film Reels; and I do declare the following to be a full, clear, and exact description of the invention, such as will enable others skilled in the art to which it 10 pertains to make and use the same.

This invention relates to improvements in motion picture film reels, having more particular reference to an alarm to be used therewith to enable the operator to determine when the end of the film has been reached so that the other machine, which is generally employed, can be started at the proper time to prevent any interruption of 20 the picture.

The principal object of the invention is to provide a device of this class embodying a film released actuator and an audible signal operated by said actuator, the latter being 25 movable to and held in a position to cause an intermittent and successive operation of the signal when a predetermined amount of the film has been unwound. Heretofore, devices of this class, so far as I am aware, because of their particular construction and arrangement only actuate the signal a single 30 time. Consequently, if the operator fails to hear the signal, the desired result is not accomplished. However, by providing a structure 35 wherein the signal will be actuated successively for a number of times, the operator will be sure to hear it one or more times. Thus, effective results with my device are insured.

Another object of the invention is to provide a film reel equipped with an alarm in the form of a bell, the latter being disposed on the exterior of the reel housing so that the operator will be sure to hear it regardless 40 of the noise brought about by the running of the machine itself.

A further object of the invention is to provide an alarm including the aforesaid bell, the latter being of the self and everset 45 type and effective operation thereof being insured.

Other objects and advantages of the invention will be apparent during the course of the following description.

In the accompanying drawings forming a 55 part of this specification and in which like numerals are employed to designate like parts throughout the same;

Figure 1 is a central vertical sectional view through a conventional type of film reel 60 and its housing equipped with a signal constructed in accordance with this invention, the latter being shown in its inoperative position.

Figure 2 is a view similar to Fig. 1, with 65 parts shown in elevation, also showing the actuator in engagement with the bell trip.

Figure 3 is a side elevation of the film reel removed from its housing, the actuator being shown in the position it assumes to operate the bell and the section being taken on the line 3—3 of Fig. 2.

Figure 4 is an enlarged detail sectional view of the bell.

Figure 5 is a sectional view taken on the 75 plane of the line 5—5 of Fig. 4.

By referring to the drawings, it will be seen that the letter H designates a housing in which a film reel R is removably mounted, being rotatable on a shaft S carried by a 80 suitable supporting bracket B. Wound on the reel is the film F. These parts are of the usual construction and constitute no part of this invention.

The invention, as before intimated, resides in the construction and arrangement of a signal which is designed to enable the operator to determine when the film is nearing its end. According to the invention, the reel R has a substantially triangular opening 1 85 formed in one of its heads adjacent its hub. Struck out from this head near the wide end of the opening are ears 2 which constitute bearings for a shaft 3 which carries a substantially triangular plate 4 which may be 90 well termed as an actuator. This actuator is released and permitted to move to its effective position when a predetermined amount of the film has been unwound, it being moved through the aforesaid opening 1 by 95 means of a coiled spring 5 which surrounds the shaft 3 and has its ends anchored in such

a manner as to move the actuator outwardly through this opening. At this point, I wish to state that the actuator could be of any other construction and shape and could be 5 pivotally mounted in various ways. I may also state, that the actuator could be formed, from the metal which is struck out from the head of the reel to provide the aforesaid opening 1.

10 Arranged on the exterior of the housing H and adapted to be operated by the aforesaid actuator, is a signal, preferably in the form of a bell 6. This bell in its preferred form includes an attaching plate or bracket 15 7 which is screwed or otherwise secured to the housing, this bracket in turn being provided with a central projection 8 to which the bell is detachably connected, and below this projection with a bored enlargement 9 constituting a bearing. Rotatable in this bearing is a relatively short shaft 10 which carries a hammer 11, the latter being automatically returned to an ineffective position after each operation by means of a coiled 25 spring 12 connected therewith and with an eye 13 on the aforesaid part 8. For the purpose of imparting rotation to the shaft 10, I make use of a trip 14 which is disposed within the housing in a position to be struck 30 by the actuator 4. I again wish to direct attention to the fact, that by disposing the signal on the exterior of the housing and close to the operator, it is sure to be heard by the operator regardless of the noise 35 caused from the operation of the machine.

In operation, the reel R is placed on the usual winding machine and the film F is wound thereon, say about six or seven times, or any desired number of times according 40 to the time which the operator wishes the signal to be actuated. After this, the actuator 4 is placed on the top of the last winding of the film and the rest of the latter is then wound on the reel and the actuator 4 becomes positioned between the 45 layers or wrappings of the film, appearing substantially as shown in Fig. 1. With the actuator in its ineffective position, the reel is placed on the shaft S in the housing H. Then, it will be seen that as the film is 50 unwound enough to uncover the member 4, the latter, due to the action of the coiled spring 5 will be swung through the opening 1 and caused to assume an angular position such as disclosed in Fig. 2. Now, as soon 55 as it is brought against the trip 14, a rocking movement will be imparted to the shaft 10, such action of parts causing the hammer 11 to strike the bell 6 and give an audible signal. Further rotation of the reel will cause the actuator 4 to become disengaged from the trip 14 and the action of the spring 12 in the bell will automatically return the hammer 11 to an ineffective position. It is 60 to be noted that inasmuch as the actuator 65

remains in the position shown in Fig. 2 after being released, it will cause a successive operation of the bell at each revolution of the reel. Thus, in case the operator fails to hear the first signal, he will be 70 bound to hear one of the later occurring signals. At this point, I wish to emphasize the fact that the substantially triangular shape of the actuator 4 insures an effective disengagement thereof from the trip 14 75 which might otherwise not occur with some other shape of actuator.

A careful consideration of the statements in the foregoing paragraphs taken in connection with the accompanying drawings is thought to be sufficient to enable persons skilled in the art to which this invention relates, to obtain a clear understanding of the same. Therefore, a more lengthy description is deemed unnecessary. 80

Advantageous and effective results are insured with the construction and arrangement herein shown and described, and for this reason, this construction and arrangement is taken as a preferred embodiment of 90 the invention. However, I wish it to be understood that various minor changes in the shape, size, and arrangement of parts may be resorted to as long as these changes do not depart from the spirit of the invention or the scope of the subjoined claims. 95

What is claimed is:

1. In a device of the class described, a film reel, a film released actuating arm carried thereby and movable to the axis of 100 and held in an angular position with respect to the reel, and a self and everset signal supported in close proximity to said arm, including a trip to be successively operated by said arm at each revolution. 105

2. In a device of the class described, a film reel having an opening adjacent its hub, spaced bearings carried by said reel, a spring operated signal actuating arm journaled in said bearings, said arm being 110 movable through the aforesaid opening when released by the film, and an automatically set signal including a trip adapted to be struck successively by said arm to operate the signal several times. 115

3. The structure set forth in claim 2, the arm being substantially triangular in shape to insure an effective disengagement thereof from the trip.

4. A device of the class described comparing a bell adapted to be secured on the exterior of a reel housing, said bell including a hammer, a spring for automatically returning the hammer to an ineffective position after each operation, a trip for moving 120 the hammer to operative position; and a film released actuator adapted to be carried by the reel for co-action with said trip to operate the latter at each revolution of the reel after projection of said actuator. 125 130

5. In a device of the class described, an attaching plate including a central extension having a screw-threaded socket at its outer end, and also including a bored enlargement 5 constituting a bearing, a bell, a screw passing through the latter and into the aforesaid screw-threaded socket, a relatively short shaft rotatable in the aforesaid bearing, a trip connected to one end of the shaft, a bell-crank secured to the other end of the shaft and including a head adapted to strike the bell, a coiled spring connected to one end of the bell-crank and to the aforesaid extension; and a film released actuator adapted for coaction with said trip. 10 15

In testimony whereof I have hereunto set my hand.

CLAUDE de ROCHEFORT-LUCAY.
